RECLINING ARTICLE OF FURNITURE

Anton Lorenz, Buffalo, N. Y.

Application February 18, 1947, Serial No. 729,289

12 Claims. (Cl. 155—106)

1

This invention relates to articles of furniture, and more particularly to reclining articles of furniture, wherein a seat, a downward extension of a back-rest and a link-chain composed of a plurality of connecting links form movable members of a link-system swingably mounted on a support, and wherein the movements of a leg-rest swingably mounted on the seat are controlled by a controlling mechanism in dependence on the movements of a member of said link-system.

An object of the present invention is to provide a new and useful controlling mechanism for the swingable leg-rest of a reclining article of furniture of above described type, by means of which the leg-rest may be readily brought into a substantially horizontal position, when the back-rest and seat are brought into an extreme reclined position.

A further object of the present invention is to equip a reclining article of furniture with a locking device, by means of which the movable members of the reclining article of furniture may be locked in one or more predetermined positions and may be frictionally held in other positions.

Another object of the present invention is to improve on reclining articles of furniture of above described type as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable reclining chair, according to the invention, a portion of a side wall of the support being broken away.

Fig. 2 is a fragmentary side elevational view illustrating the locking device of the chair shown in Fig. 1 in an enlarged scale.

Fig. 3 is a side elevational view of a different embodiment of a locking device which may be used in the chair shown in Fig. 1.

Fig. 4 is a side elevational view of a different embodiment of an adjustable reclining chair according to the invention, a portion of a side wall of the support being broken away.

Fig. 5 is a side elevational view of another embodiment of an adjustable reclining chair according to the invention, a portion of a side wall of the support being broken away.

Fig. 6 is a side elevational view of a further embodiment of an adjustable reclining chair according to the invention, a portion of a side wall of the support being broken away.

2

Fig. 7 is a side elevational view of another embodiment of a reclining chair according to the invention, a portion of a side wall of the support being broken away, and

5 Fig. 8 is a side elevational view of a further embodiment of a reclining chair according to the invention, a portion of a side wall of the support being broken away.

Referring now to Fig. 1, 10 generally indicates

10 a support substantially in the shape of a casing.

The rear end portion of a seat 12 is pivoted to the support 10 at 14. A back-rest 16 is pivotally mounted on the support 10 at 18 at a point spaced from the pivotal connection 14 between the seat 12 and the support 10. The back-rest 16 has a downward extension 20 projecting downwardly below the plane of the seat 12. The adjustable reclining chair comprises at each of its sides a link-chain including a bent lower connecting link 22 and a front connecting link 24 pivotally connected with each other at 26. The rear end of said link-chain, i. e., the rear end portion of the lower connecting link 22, is pivoted to the downward extension 20 of the back-rest 16 at

15 28; the front end of the link-chain, i. e., the upper end portion of the front connecting link 24, is pivoted to the seat 12 at 30. Said seat 12, said downward extension 20 of the back-rest 16 and said link-chain 22, 24 form the movable

20 30 members of a link-system swingably mounted on the support 10 as described above. The movements of the movable members of said link-system are controlled by guiding means or a guiding link 32 associated with the support 10

25 35 and a link of the link-chain; according to Fig. 1, one end of the guiding link 32 is pivoted to the support 10 at 34, the other end of said guiding link 32 is pivotally connected with an intermediate point of the lower connecting link 22 at 36.

30 40 A leg-rest 38 is swingably mounted on the front portion of the seat 12 at 40. On each side of the chair, one end of a controlling link 42 passing through a slot 44 of the front wall of the casing-like support 10 is pivoted to said leg-rest 38 at 46, the other end of said controlling link 42 is pivoted to an intermediate point of the lower connecting link 22 at 48. Thus, the movements

35 45 50 of the swingable leg-rest 38 are controlled by the controlling link 42 in dependence on the movements of the lower connecting link 22 of the link-chain 22, 24.

The sitting position of the movable members of the chair is limited by the upper edge of the casing-like support 10 on which the seat 12 comes to a rest. When the occupant of the chair leans the weight of his body against the back-rest 16 and swings same into a reclined position, for example, the extreme reclined position 16' limited by the edge 50 of the rear wall of the support 10

60 cooperating with the back-rest, the seat 12 is

swung into the reclined position 12' through the medium of above described link-system, and the leg-rest 38 is brought into the substantially horizontal position 38' through the medium of the controlling link 42 arranged between the leg-rest 38 and the lower connecting link 22.

As best shown in Figs. 1 and 2, the adjustable reclining chair is provided with a locking device generally indicated by 52. Said locking device 52 comprises a rockable lever 54 swingably mounted on the swingable seat 12 at 56. Said rockable lever 54 is provided with a handle 58 for manual actuation. Furthermore, said rockable lever 54 is provided with a slot 60 and a notch 62 communicating with said slot 60 at one side thereof. A stationary locking pin 64 or the like mounted on a side wall of the support 10 is arranged for engagement with said slot 60 on said notch 62. A tension spring 66 stretched between a point 70 of said rockable lever 54 and a point 70 of the seat 12 tends to urge said notch 62 into locking engagement with said locking pin 64 when said locking pin 64 is in register with said notch, as shown in Figs. 1 and 2 in full lines. When the locking pin 64 and the notch 62 are not in register with each other as shown in dash-and-dot lines in Fig. 2, the spring 66 tends to urge the side of the slot 60 communicating with the notch 62 against said locking pin 64. The notch 62 is arranged at such a point of the lever 54, that said notch 62 is in register with said locking pin 64 when the seat 12 and the other movable members of the chair are in their sitting position. Therefore, when the movable members of the chair are brought from a reclined position into the sitting position, the locking pin 64 snaps automatically into the notch 62 by the action of the spring 66, whereby the movable members of the chair are mechanically locked in the sitting position. If it is desired to bring the movable members of the chair from the sitting position into a reclined position, the rockable lever 54 is swung in counter-clockwise direction (as viewed in Fig. 2) by means of the handle 58, whereby the locking pin 64 is brought into register with the slot 60. Thereupon the movable members of the chair may be brought into a reclined position, as now the slot 60 may slide along the locking pin 64. As, after a release of the handle 58, the spring 66 urges a side of the slot 60 against the locking pin 64, a friction is caused between the lever 54 and the pin 64 which may be of sufficient degree to hold or to assist in the holding of the movable members of the chair in any intermediate position.

According to the embodiment of a locking device 52a shown in Fig. 3, the rockable lever 54a is provided with a slot 60a communicating with a series of notches 62a. The uppermost notch 62a is arranged in such a position that it snaps automatically into engagement with the locking pin 64a mounted on the support by the action of the spring 66a when the seat 12 and the other movable members of the chair are in their sitting position. The lowermost notch 62a is arranged in such a position that it automatically snaps into locking engagement with the locking pin 64a by the action of the spring 66a when the seat 12 and the other movable members of the chair are in their extreme reclined position. The arrangement of a series of notches 62a permits the mechanical locking of the movable members of the chair in several predetermined positions. Of course, each time when the movable members of the chair shall be released from a locked posi-

tion, the rockable lever 54 must be swung by means of the handle 58a about the pivot 56a in counter-clockwise direction so as to bring the locking pin 64a and the slot 60a in register with each other.

Of course, the reclining chair shown in Fig. 1 may also be equipped with another locking device, if desired.

According to the embodiment of a reclining chair shown in Fig. 4, the seat 112 and the back-rest 116 are pivotally connected with each other at 118 at a point coaxial with the pivotal connection 118 between the back-rest 116 and the support 110. The reclining chair comprises on each of its sides a link-chain including a lower connecting link 122, an intermediate connecting link 172 and a front connecting link 124 pivotally connected with each other at 174 and 176 respectively. The rear end of said link-chain 122, 172, 124 is pivoted to the downward extension 120 of the back-rest 116 at 128. The front end of said link-chain 122, 172, 124 is pivoted to the seat 112 at 130. The movements of the movable members of the link-system formed by the seat 112, the downward extension 120 of the back-rest 116, and the link-chain 122, 172, 124 are controlled by a guiding link 132, the upper end of which is pivoted to the support 110 at 134 and the lower end portion of which is rigidly connected with the intermediate connecting link 172.

The movements of a leg-rest 138 swingably mounted on the seat 112 at 140 are controlled by a controlling link 142, one end of which is pivoted to the leg-rest 138 at 146, and the other end of which is pivoted at 178 to an extension 180 of the lower connecting link 122 projecting beyond the pivotal connection 174 between the lower connecting link 122 and the adjacent intermediate connecting link 172 of the link-chain 122, 172, 124.

The sitting position of the movable members of the chair shown in full lines is limited by a stop 182 mounted on the support 110 for cooperation with the downward extension 120 of the back-rest 116. The extreme reclined position of the movable members of the chair shown in dash-and-dot lines is limited by the stop 150 formed by an edge of the rear wall of the support 110 cooperating with the back-rest 116.

According to the embodiment of a chair shown in Fig. 5, the back-rest 216 is pivoted to the support 210 at 218. The rear end portion of the seat 212 is pivotally connected with the back-rest 216 at 218 at a point coaxial with the pivotal connection 218 between the back-rest 216 and the support 210. The rear end of a link-chain comprising a lower connecting link 222 and a front connecting link 224 pivotally connected with each other at 226 is pivoted to the downward extension 220 of the back-rest 216 at 228. The front end of said link-chain 222, 224 is pivoted to the seat 212 at 230. The movements of the link-system 212, 220, 222, 224 are controlled by a guiding link 232 pivoted to the support 210 at 234 and pivoted to the lower connecting link 222 at 236.

The movements of a leg-rest 238 swingably mounted on the seat 212 at 240 are controlled by a controlling link 242 pivoted at one of its ends to the leg-rest 238 at 246. The other end of said controlling link 242 is pivoted to an intermediate point of the front connecting link 224 at 284. Thus, the movements of the swingable leg-rest 238 are controlled by the controlling link 242 in

dependence on the movements of the front connecting link 224 of the link-chain 222, 224.

The sitting position of the movable members of the chair shown in full lines is limited by the upper edge of the support 210 cooperating with the seat 212. The extreme reclined position of the movable members of the chair is limited by the edge 250 of the rear wall of the support 210 cooperating with the back-rest 216.

According to the embodiment of a chair shown in Fig. 6, the link-system 312, 320, 322, 324 swingably mounted on the support 310 at 318 corresponds to the link-system of the chair shown in Fig. 5; likewise, the movements of said link-system are again controlled by a guiding link 332, one end of which is pivoted to the support 310 at 334, the other end of which is pivoted to the lower connecting link 322 at 336.

According to Fig. 6, however, one end of the controlling link 342 is in pivotal connection with the pivotal connection 336 between the lower connecting link 322 and the front connecting link 324; the other end of said controlling link 342 is pivoted at 346 to the leg-rest 338 swingably mounted on the seat 312 at 340.

The sitting position of the movable members of the chair shown in full lines is limited by the upper edge of the support 310. The extreme reclined position of the movable members of the chair shown in dash-and-dot lines is limited by the edge 350 of the rear wall of the support 310.

According to the embodiment of a chair shown in Fig. 7, the rear end portion of a seat 412 is pivoted to the support 410 at 414. A back-rest 416 is pivoted to the support 410 at 418 at a point spaced from the pivotal connection 414 between the seat 412 and the support 410. The link-chain comprises a lower connecting link 422 and a front connecting link 424 pivotally connected with each other at 426. The rear end of said link-chain 422, 424 is pivoted to the downward extension 420 of the back-rest 416 at 428, the front end of said link-chain 422, 424 is pivoted to the seat 412 at 430. The movements of the link-system 412, 420, 422, 424 are controlled by a guiding link 432 pivoted to the support at 434 and pivoted to the lower connecting link 422 at 436.

The front connecting link 424 is provided with an extension 486 projecting beyond its pivotal connection 426 with the adjacent lower connecting link 422 of the link-chain 422, 424. The controlling link 442 is pivoted to one of its ends to said extension 486 of the front connecting link 424 at 488; the other end of said controlling link 442 is pivoted at 446 to the leg-rest 438 swingably mounted on the seat 412 at 440.

The sitting position of the movable members of the chair is limited by a stop 482 mounted on the support 410 for cooperation with the downward extension 420 of the back-rest 416. The extreme reclined position of the movable members of the chair is limited by the edge 450 of the rear wall of the support 410 cooperating with the back-rest 416.

According to Fig. 8 the back-rest 516 is pivoted to the support 510 at 518. The seat 512 is pivotally connected with the back-rest 516 at a point coaxial with the pivotal connection 518 between the back-rest 516 and the support 510. The link-chain comprises the lower connecting link 522 and the front connecting link 524 pivotally connected with each other at 526. The rear end of said link chain 522 is pivoted to the downward extension 520 of the back-rest at 528, the front end of said

link-chain 522 is pivoted to the seat 512 at 530. The movements of the link-system 512, 520, 522, 524 are controlled by a guiding link 532. One end of said guiding link 532 is pivoted to the support 510 at 534, the other end of said guiding link 532 is pivotally connected with the pivotal connection 526 between the lower connecting link 522 and the front connecting link 524.

The front connecting link 524 has an extension 586 projecting beyond the pivotal connection 526 between the front connecting link 524 and the lower connecting link 522 and being arranged at an angle to the longitudinal axis of the front connecting link 524. One end of the controlling link 542 is pivoted to said extension 586 of the front connecting link 524 at 588. The other end of said controlling link 542 is pivoted to the leg-rest 538 at 546. The leg-rest 538 is swingably mounted on the seat 512 at 540.

The sitting position of the movable members of the chair shown in full lines is limited by an abutment of the downward extension 520 of the back-rest 516 against the rear wall of the support 510. The extreme reclined position of the movable members of the chair shown in dash-and-dot lines is limited by a hook-like portion 590 arranged on the extension 586 of the front connecting link 524 for cooperation with the controlling link 542.

I have described preferred embodiments of my invention, but it is understood that this disclosure is for the purpose of illustration, and that various omissions and changes in shape, proportion and arrangement of parts, as well as the substitution of the equivalent elements for the elements shown and described may be made without departing from the spirit and scope of the invention as set forth in the appended claims.

For example, the controlling mechanism of the leg-rest by means of a controlling link pivoted to the leg-rest and a connecting link of a link-chain of a reclining article of furniture may also be applied to reclining articles of furniture provided with a link-system of a type other than that shown in the drawings; for example, the movements of the movable members of such a link-system could be controlled by guiding means in the shape of cooperating sliding means.

Furthermore, each of the chairs shown in Figs. 4-8 may be provided with a locking device either of the type shown in Figs. 1 and 2 or of any other type for holding the movable members of the chair in a predetermined position.

Moreover, the locking device shown in Figs. 1 and 2 may also be applied to different types of articles of furniture, wherein a movable member of such an article of furniture shall be held or locked in a predetermined position.

Furthermore, the invention may be applied to articles of furniture other than the type of chairs shown in the drawings, for example, to office chairs, chairs for use in railroad cars, chairs for use in airplanes, lounges, etc.

What I claim is:

1. An article of repose for supporting the body of a person comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of the chain and a front connecting link at the other end of the chain, at least one of said

connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to one of said connecting links, and the other end portion of said controlling link being pivoted to said leg-rest.

2. In an article of repose for supporting the body of a person as claimed in claim 1, said guiding means being engaged with the lower connecting link.

3. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding link and a chain of connecting links including a lower connecting link at one end of the chain and a front connecting link at the other end of the chain, at least one of said connecting links being arranged below the plane of the seat-member, the upper end of said guiding link being pivoted to said support, the lower end of said guiding link being connected with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to one of said connecting links, and the other end portion of said controlling link being pivoted to said leg-rest.

4. In an article of repose for supporting the body of a person as claimed in claim 3, said guiding link being connected with the lower connecting link.

5. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of a chain and a front connecting link at the other end of the chain, at least one of said connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end

portion of said controlling link being pivoted to said lower connecting link, and the other end portion of said controlling link being pivoted to said leg-rest.

6. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of the chain and a front connecting link at the other end of the chain, at least one of said connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to an intermediate point of the lower connecting link, and the other end portion of said controlling link being pivoted to said leg-rest.

7. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of the chain and a front connecting link at the other end of the chain, said lower connecting link and said front connecting link being pivotally connected with each other, at least one of said connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivotally connected with said lower connecting link in coaxial alignment with the pivotal connection between the lower connecting link and the front connecting link, and the other end portion of said controlling link being pivoted to said leg-rest.

8. In an article of repose for supporting the body of a person as claimed in claim 7, said guiding means being engaged with the lower connecting link.

9. An article of repose for supporting the body of a person, comprising in combination: a support, a constrained linkage having stationary link-means and a plurality of movable links, said stationary link-means being included in said support, said movable links including a seat-member, a downward extension of a back-rest

member, a guiding means and a chain of connecting links including a lower connecting link at one end of the chain and a front connecting link at the other end of the chain, said lower connecting link having an extension projecting beyond its pivotal connection with the adjacent connecting link, at least one of said connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to said extension of the lower connecting link, and the other end portion of said controlling link being pivoted to said leg-rest.

10. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of the chain and a front connecting link at the other end of the chain, at least one of said connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to said front connecting link, and the other end portion of said controlling link being pivoted to said leg-rest.

11. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of the chain and a front connecting link at the other end of the chain, at least one of said connecting links being arranged below the plane of the seat-member, said guiding means being connected to said support and engaged with at least one connecting link of said chain of connecting links, said lower connecting link being

pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to an intermediate point of said front connecting link, and the other end portion of said controlling link being pivoted to said leg-rest.

12. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding means and a chain of connecting links including a lower connecting link at one end of the chain and a front connecting link at the other end of the chain, said front connecting link having an extension projecting beyond its pivotal connection with the adjacent connecting link, at least one of said connecting links being arranged below the plane of the seat-member, said guiding means being connected to said support and engaged with at least one connecting link of said chain of connecting links, said lower connecting link being pivoted to the downward extension of the back-rest member, said front connecting link being pivoted to the front portion of said seat-member, means pivotally connecting at least one of said back-rest- and seat-members with said support, a leg-rest swingably mounted on the front portion of the seat-member, and a controlling link, one end portion of said controlling link being pivoted to said extension of the front connecting link, and the other end portion of said controlling link being pivoted to said leg-rest.

ANTON LORENZ.
